UNITED STATES PATENT OFFICE.

MARTIN A. SMITH, OF BUCKLAND, OHIO.

FENCE-POST.

No. 830,103.

Specification of Letters Patent.

Patented Sept. 4, 1906.

Application filed February 21, 1906. Serial No. 302,269.

To all whom it may concern:

Be it known that I, MARTIN A. SMITH, a citizen of the United States, residing at Buckland, in the county of Auglaize and State of Ohio, have invented new and useful Improvements in Fence-Posts, of which the following is a specification.

My invention pertains to the kind of fence-posts that are formed of cement or other plastic material and metal; and it consists in the peculiar and advantageous post hereinafter described, and particularly pointed out in the claims appended.

In the accompanying drawings, forming part of this specification, Figure 1 is a perspective view illustrating my novel post as carrying a portion of woven-wire fence material and a crown-runner of barbed wire or other suitable material. Fig. 2 is a longitudinal or vertical section of the post, taken in a plane at right angles to the stretch of woven-wire fence material. Fig. 3 is a horizontal section taken through the post in a plane slightly above the lowermost staple. Fig. 4 is a detail vertical section illustrating the arrangement of the upper staples in the body of the post. Fig. 5 is a detail view of the metallic core removed.

Similar letters of reference designate corresponding parts in all of the views of the drawings.

A is the body of my novel fence-post, which is formed of cement or other plastic material and may be rectangular in cross-section, as shown, or of any other suitable shape.

B is the metallic core, which extends throughout the major portion of the length of the body, Fig. 2. The said metallic core is preferably composed of three (more or less) wires *a* and comprises a shank *b*, formed by twisting the wires, and lower and upper arms *c*, extending from the ends of the shank. When positioned in the body A, as illustrated, the said core as a whole will lend strength to the body, while the arms *c* will tie the lower and upper portions of the body to the core and in that way prevent disintegration of the plastic material.

C are horizontal staples arranged at one side of the body A and at intervals in the height thereof. The said staples respectively comprise a loop or bight *d* and legs *e*, diverging from the inner ends of the loop. The said staples C, like the metallic core B, are secured in the body A at the time of manufacture, and by reason of the legs *e* diverging,

as stated, it will be apparent that the material of the body A will effectually prevent withdrawal or displacement of the staples.

D are vertical staples, having loops *d* extending upwardly from the upper end of the body A and also having diverging legs *e* secured in the material of the body. These vertical staples D in common with the horizontal staples C are designed to receive the fastening-wire E. (Best shown in Fig. 1.) The said fastening-wire E is extended through the several staples C and D and is connected at its lower end to the lowermost of the staples D, and after being passed through the vertical staples D has its end portion bent downwardly against the side of the body A opposite to that carrying the staples D and in that way secured in position, as indicated by *f* in Fig. 2.

F is a stretch of woven-wire fence material, and G is a crown-runner, preferably composed of barbed wire, as illustrated. The stretch of woven-wire fence material is arranged against the side of the body A, bearing the staples C, in such manner that its interstices receive the said staples and is interposed between the said side of the body and the fastening-wire E. From this it follows that the several staples C will support the stretch F and prevent vertical movement thereof, while the wire E will securely hold the stretch against the side of the body and effectually prevent disconnection of the one from the other. The crown-runner G extends between the two vertical staples D and under the upper portion of the fastening-wire E, and consequently there is no liability of the said runner being casually moved off of or disconnected from the post-body A.

It will be gathered from the foregoing that my novel post is simple and inexpensive, and yet is well adapted to withstand the weather and the ordinary rough usage to which fence-posts are subjected. It will also be gathered that the stretch of fence material F and the crown-runner G are strongly connected to the body A through the medium of the fastening-wire E and the staples C and D, and hence the fence structure as a whole is a strong and durable one.

I have specifically described the construction and relative arrangement of the parts embraced in the present and preferred embodiment of my invention in order to impart a definite understanding of the said embodiment. I do not desire, however, to be un-

derstood as confining myself to the said specific construction and relative arrangement of parts, as such changes or modifications may be made in practice as fairly fall within 5 the scope of my invention as claimed.

Having described my invention, what I claim, and desire to secure by Letters Patent, is—

1. A fence-post comprising a body of plastic material, and a core embedded in the body; the said core having a shank located in the longitudinal center of the body and formed by a plurality of twisted wires and also having arms *c* extending outward in opposite directions at the upper end and the lower end of the shank, each of which arms *c* is formed by one of the said wires.

2. A fence-post comprising a body of plastic material, a plurality of staples secured in one side of the body at intervals in the height thereof, a plurality of staples secured in the upper end of the body, and a fastening-wire passed through the several staples, and secured at one end to the lowermost of the first-mentioned series of staples and suitably secured at its upper end.

3. A fence-post comprising a body of plastic material, a plurality of staples secured in one side of the body at intervals in the height thereof, a plurality of staples secured in the upper end of the body, and a fastening-wire passed through the several staples, and se-

cured at one end to the lowermost of the first-mentioned series of staples and having its opposite end bent down against the side of the 35 post remote from that bearing the first-mentioned series of staples.

4. In a fence, the combination with a post comprising a body of plastic material, a plurality of staples secured in one side of the 40 body at intervals in the height thereof, a plurality of staples secured in the upper end of the body, and a fastening-wire passed through the several staples and secured at one end to the lowermost of the first-mentioned series of staples and suitably secured 45 at its upper end; of a stretch of woven-wire fence material arranged against the said side of the post so that its interstices receive the first-mentioned series of staples and it is held 50 against the post-body by the vertical portion of the fastening-wire, and a crown-runner arranged on top of the post-body and between the second-mentioned series of staples and under the horizontal portion of the fastening-wire.

In testimony whereof I have hereunto set my hand in presence of two subscribing witnesses.

MARTIN A. SMITH.
